HEATER

John R. Weaver, Camp Hill, Pa.

Application December 30, 1941, Serial No. 424,993

7 Claims. (Cl. 122—336)

This invention relates to heaters and more particularly to a heater of the flash type.

An object of this invention is to provide a heater designed for burning of very fine fuel such as coal, so that there will be substantially no ash remaining after the fuel has burned.

Another object of this invention is to provide a heater of this type which includes a pre-heating means for pre-heating the air which is mixed with the fuel in order that the fuel will burn to the desired degree.

Another object of this invention is to provide a heater of this kind which includes a pre-heater for the air mixed with the fuel in the combustion chamber and a steam generator adapted to generate steam from the products of combustion.

A further object of this invention is to provide in a heater of this kind an improved means for initially burning a predetermined quality of fuel and for initially pre-heating the air entering the combustion chamber, the device including pivoted dampers which are connected together for simultaneous operation, one of the dampers permitting the exhaust of air from the pre-heating chamber during the starting of the heater, and the other of the dampers substantially cutting off the exhaust of hot air from the steam chamber, so that during the starting operation of the heater the products of combustion are utilized for pre-heating the air entering the combustion chamber, and subsequently the damper for the pre-heating chamber is practically cut off, and the damper for the steam chamber is turned open, in order to permit the flow of heated air or gases through the steam chamber.

A further object of this invention is to provide an improved means for feeding both air and very fine coal or fuel to the heater.

To the foregoing objects and others which may hereinafter appear, the invention consists of the novel construction, combination and arrangement of parts as will be more specifically referred to and illustrated in the accompanying drawings, but it is to be understood that changes, variations and modifications may be resorted to which fall within the scope of the invention as claimed.

In the drawings:

Figure 1 is a detail top plan partly broken away and in section of a heater constructed according to an embodiment of this invention.

Figure 2 is a sectional view taken on the line 2—2 of Figure 1.

Figure 3 is a sectional view taken on the line 3—3 of Figure 2, and

Figure 4 is a detail side elevation partly broken away and in section of a modified form of this invention including diagrammatically the electric circuits associated with the modification.

Referring to the drawings the numeral 10 designates generally a housing which is formed of a top wall 11, a bottom wall 12, a front end wall 13, and a rear end wall 14. The walls 11, 12, 13, and 14 may be formed of refractory material, and it will be understood that, if desired, an outer insulating jacket may be disposed about the outer sides and top wall of the housing 10.

An inner transversely disposed wall or partition 15 is disposed within the housing 10 and has the upper end 16 thereof disposed in downwardly spaced relation with respect to the inner side of the top wall 11, so as to thereby provide a passage 17 which communicates a pre-heating chamber 18 with a combustion chamber 19. An inner horizontally disposed wall 20 is secured between the side walls 21 and is also secured to the inner vertical wall 15 thereby dividing a portion of the housing 10 into an upper combustion chamber 19 and the lower steam chamber 22. The front wall 13 at the lower portion thereof is provided with an opening 23, and an ash door 24 is disposed on the outer side of the wall 13 for closing the opening 23. The door 24 permits entrance to the lower portion of the steam chamber 22 in order to remove the ashes or the like which may accumulate within the steam chamber 22.

The wall 20 constitutes the bottom wall for the combustion chamber 19 and also constitutes the top wall for the steam chamber 22. The forward end of the wall 20 is disposed in inwardly spaced relation with respect to the inner side of the front wall 13 thereby providing a passage 25 communicating the combustion chamber 19 with the steam chamber 22.

The steam chamber 22 has mounted therein a steam generating structure generally designated as 26. The generator 26 includes a plurality of vertically disposed coils 27 which are connected together at the center thereof, and an inlet nipple or connection 28 is connected to the lower portion of the generator 26, and extends through a side wall 21 for connection with a source of water supply. An upper steam outlet connection 29 is connected with the upper portion of the generator 26 and extends outwardly or laterally through the opposite side wall 21 from the connection 28.

The pre-heating chamber 18 has connected therewith an outwardly extending pipe or duct

30 in the lower portion thereof, and the steam chamber 22 has also connected therewith and extending therefrom an exhaust or outlet duct or pipe 31. The pipes or ducts 30 and 31 are connected to a common exhaust or outlet pipe 32 which may be extended to a stack or the like. A damper 33 is pivotally mounted in the duct 30 and has a crank or arm 34 exteriorly of the pipe 30. A second damper or valve 35 is pivotally carried by the pipe or duct 31 and is provided with an arm or lever 36 exteriorly of the pipe or duct 31. A damper operating rod 37 is pivotally connected at 38 with the arm or crank 34, and is also pivotally connected as at 39 with the arm or crank 36, so that the two dampers 33 and 35 will operate together.

Preferably as shown in Figure 1 the damper 33 will be disposed in substantially an open position when the damper 35 is substantially closed. This is the starting position of each damper at the time the heater is initially set in operation. After the heater has been in operation a short time, so that the air passing through the pre-heating chamber 18 is heated to the desired degree for flash burning of the fuel discharged in the combustion chamber 19, the positions of the dampers 33 and 35 will be reversed, that is, the damper 33 will be substantially closed whereas the damper 35 will be substantially open.

The pre-heating chamber 18 has mounted therein an air pre-heating coil structure generally designated as 40. The pre-heating structure 40 includes a plurality of coils 41 which are connected at the lower ends as at 42 and are connected together at their upper ends as at 43. An intake nipple 44 is connected with the lower portion of the coil structure 40, and an exhaust nipple 45 is connected with the upper portion of the coil structure 40 and extends from the coil structure oppositely from the nipple 45.

The nipple 45 is extended through the inner wall 15 through an opening 46 formed in the wall 15, and a nozzle 47 is carried by the nipple 46, and extends into the lower portion of the combustion chamber 19, so that the pre-heated air discharged from the nozzle 47 will provide the desired oxygen to permit the ready burning of the fuel within the combustion chamber 19.

An air duct generally designated as 48 is connected with the intake nipple 44 and includes a lower horizontal nipple or pipe connection 49 having an elbow 50 connected therewith. The pipe connection 49 extends through the rear wall 14 of the housing 10 and is connected with the intake nipple 44. An upwardly extending branch 51 is connected with the elbow 50 and has mounted on the upper end thereof an elbow 52. A manually operable damper 53 is mounted in the lower portion of the pipe 51, so as to provide a means for regulating the quantity of air passing from the pipe structure 48 into the pre-heating coil 40.

A horizontally disposed pipe or branch 54 is connected at one end with the elbow 52 and is connected at the other end to a right angular branch 55. The branch 55 is connected with a T coupling 56, and an axially disposed pipe 57 is connected with the T 56 and is also connected to an L 58. A pipe 59 is connected with the L 58, and the pipe 59 is also connected with a blower structure generally designated as 60. The blower 60 has a fan blade structure 61 mounted in the housing 62, and a fan blade shaft 63 is journalled through the housing 62. An electric motor 64 is directly coupled to the shaft 63 and is adapted to

be connected to a suitable source of electric current supply.

A coal or fuel hopper 65 is mounted on the top wall 11 of the housing 10, being supported by 5 means of supporting members 66 which are fixed to the upper side of the top wall 11. The hopper 65 has journalled in the lower portion thereof a screw conveyor 67 which is directly coupled to the shaft 63. A conveyor housing 68 extends from 10 one side of the hopper 65 and includes an end wall 69 formed with a discharge opening 70. The quantity of coal discharged through the opening 70 by means of the conveyor 67 is regulated by 15 means of an adjustable needle valve member 71. The needle valve member 71 is formed of a head 72 carried by a threaded shaft 73 extending through a valve housing 74. The valve housing 74 is formed in a pipe or air duct 75 which extends at right angles from the conveyor housing 68 as 20 shown in Figure 1.

One end of the pipe structure 75 is connected to a branch 76 of the T 56 by means of a flanged coupling 77. A manually adjustable damper 78 is mounted in the pipe 75 adjacent the coupling 25 77, so as to provide a means for regulating the quantity of air passing from the coupling 56 into the pipe 75. The pipe 75 extends rearwardly from the conveyor housing 68 and has connected therewith a downwardly and rearwardly inclined 30 fuel discharge nozzle or pipe 79. The pipe or nozzle 79 has a flange 80 which is fixed by fastening devices 81 to the upper side of the top wall 11. The inclination of the fuel discharge member 70 is downwardly and rearwardly in the direction of the air nozzle 47, so that the fuel discharged from the nozzle structure 79 will be directed at an obtuse angle to the flow of air discharging from the air nozzle 47. In this manner the heated air discharging from the nozzle 47 will break up or spread the fuel which is discharged from the discharge member 79 at the same time that this fuel is ignited.

In order to provide a means whereby access may be had to the combustion chamber 19 for 45 placing a quantity of fuel in the combustion chamber 19 to start the heater, I have provided an upstanding nipple or upwardly opening housing 82 which is carried by the top wall 11 rearwardly of the fuel nozzle or discharge member 79. A cap 83 is adapted to engage over the housing or nipple 82 and is hingedly mounted as at 84 on the rear side of the nipple or housing 82.

Referring now to Figure 4 there is disclosed a slightly modified form of regulating means for 55 regulating the operation of the heater. In this form the heater 10^a is constructed identical with the heater 10, being formed with a pre-heating air chamber 18^a and also a steam heating chamber adjacent the air heating chamber 18^a. An 60 exhaust pipe 31^a is connected at one end with the steam chamber in the housing 10^a, and a second exhaust pipe 30^a is connected at one end with the air heating chamber 18^a. The two pipes 30^a and 31^a are extended upwardly in a convergent 65 relation, being connected at their upper ends to a substantially V-shaped coupling generally designated as 85. The coupling 85 has a branch 86 which is connected with the pipe 31^a and also has a second branch 87 connected with the upper end 70 of the pipe 30^a. An air regulating valve or damper 88 is pivotally mounted on a shaft 89 within the coupling 85 in a position whereby the damper or valve 88 may control the flow of exhaust air through either one of the pipes 30^a or 31^a to a common exhaust pipe 90 which is con-

nected with the upper or convergent end of the coupling 85.

The shaft 89 has secured thereto one end of a shaft operating fork or lever 91. The forked lever 91 has slidably through the outer or bifurcated end thereof the upper end portion of a valve or damper operating rod 92. The rod 92 has mounted thereon a collar 93 which is fixed to the rod 92 above the forked end of the lever 91. A second collar 94 is mounted on the rod 92 below the lever 91, and a spring 95 is interposed between the collar 94 and the lower side of the lever 91.

The lower end of the rod 92 is pivotally connected as at 96 to one arm 97 of a bell crank 98. The bell crank 98 is pivotally mounted as at 99 on a bracket or supporting member 100 which is fixed to the rear end wall 14^a of the housing 10^a. The other arm 101 of the bell crank 98 is pivotally connected as at 102 to a horizontally slidably bell crank operating rod 103. Preferably the arm 101 is formed with an elongated slot 104 within which the pivotal member 102 slidably engages. The rod 103 is slidably through a bushing or sleeve 105 which is extended through the end wall 14^a. A heat expansive thermal member 106 is mounted on the inner end of the rod 103 within the heating chamber 18^a. The outer end of the thermostatic member 106 is fixedly secured to a collar 107 which is fixed relative to the sleeve 105. The opposite or inner end of the thermostatic member 106 is fixed as at 108 relative to the inner end of the rod 103. In this manner when the heating chamber 18^a reaches a pre-determined temperature, the thermostatic member 106 will expand, thereby moving the rod 103 inwardly and pulling the rod or link 92 downwardly.

Downward movement of the rod 92 will cause the collar 93 to engage the lever 91 and rock the damper 88 to the right or the dotted line position shown in Figure 4. In this dotted line position the air will be cut off from the pipe 30^a to the outlet pipe 90 and the air from the pipe 31^a will flow freely into the outlet pipe 90.

In order to provide a means whereby the motor 64^a associated with the heater housing 10^a may be regulated in its operation by means of the thermostatic member 106, and the movement of the damper or valve 88, I have provided a switch structure 109 which is disposed adjacent the upper end of the rod 92. The switch structure 109 is connected as at 110 with the upper end of the rod 92, so that the switch 109 will snap on and off with vertical movement of the rod 92. One side of the switch 109 is connected by means of a conductor 111 to one side of the motor 64^a, and the other side of the switch is connected by a conductor 112 to a source of current supply. The other side of the motor 64^a is connected by means of a conductor 113 to the other side of the current supply.

A second thermostatic control 114 is mounted in the steam chamber of the housing 10^a and is connected to the conductors 111 and 112 by conductors 115 and 116 respectively. The control 114 is normally closed and is adapted to break the circuit to the motor 64^a when the steam chamber becomes heated beyond a pre-determined degree. During the normal running of the furnace 10^a the switch 109 will be open and the damper 88 will be in the position shown in dotted lines. At this time the control 114 will be in a circuit closing position so as to thereby maintain operation of the motor 64^a.

In the use and operation of this heater the closure 83 is initially raised to permit the placement of charcoal or other fuel on the upper side of the inner horizontal wall 20 and within the combustion chamber 19. At this time the dampers 33 and 35 will be in the positions shown in Figure 1 wherein the damper 35 is in substantially a closed position. A small quantity of heated air may, however, pass the damper 35.

10 The blower 60 is then operated by the motor 64 so as to force air through the pre-heating coil 40. In view of the fact that the damper 35 is in a substantially closed position, the major portion of the air discharged into the combustion chamber 19 will flow rearwardly over the upper edge 16 of the inner wall 15 as shown by the arrow 114. This heated air will move downwardly in the pre-heating chamber 18 and will exhaust through the exhaust pipe or duct 30.

15 During the starting of the fire within the combustion chamber 19, the damper 78 may be in a substantially closed position, so that no air will flow through the pipe 75. After the air in the heater including the combustion chamber 19 and

20 the super-heater chamber 18 becomes heated to the desired degree, the damper 78 may be opened so as to permit air to flow through the pipe 75 and through the discharge member 79. In view of the fact that the conveyor 68 is continuously operated, the opening of the needle valve 72 will permit the fuel to be forced out of the conveyor housing 68 into the pipe 75 where the fuel is forced rearwardly and discharged with a small quantity of air through the discharge member 79.

25 As soon as the fuel is discharged from the discharge nozzle 79 this fuel will become ignited by reason of the hot blast of air being discharged from the super-heater air nozzle 47. When the fuel is being discharged from the nozzle 79 into the combustion chamber 19 and is ignited in the combustion chamber, the heated air will flow through the passage 25 into the steam chamber 22 and then exhaust through the exhaust pipe or duct 31. At this time the valve 35 is in a

30 substantially open position and the valve 33 is in a substantially closed position. While the major portion of the air heated within the combustion chamber 19 including the products of combustion are discharged through the passage 25, a portion of the heated air and products of combustion will move rearwardly through the passage 17 into the pre-heating chamber 18.

35 The heated air passing into the pre-heating chamber 18 will heat the coil 40, so that the air passing through the coil 40 will become heated prior to its discharge from the nozzle 47. In view of the fact that the damper 33 during the full operation of the furnace or heater 10 is never completely closed, the heated air in the 40 heat chamber 18 will flow from this chamber through the duct 30 into the exhaust duct 32.

45 The heater hereinbefore described will keep very high temperatures during all stages of operation which are necessary for the complete combustion of the fuel, and by means of the thermostatic control disclosed in Figure 4 the pre-heater may be substantially cut off after high temperatures develop in the combustion chamber.

50 During the time that the heater is in operation the super-heating coil 40 will be heated to a pre-determined degree and by reason of the flow of substantially cool air therethrough, the coil will not become overheated. This overheating of the super-heater 40 is also prevented by 55 reason of the fact that only a small portion of

the heated air or products of combustion from the combustion chamber 19 flow into and through the super-heating chamber 18.

What I claim is:

1. A heater comprising a housing formed of bottom, top, opposite end and side walls, an upright inner wall inwardly from one end wall and spaced at its upper end from said top wall and forming a pre-heating chamber adjacent one end of the housing, a horizontal inner wall fixed to said upright wall and to said side walls, one end of said horizontal wall being spaced from the other end wall, the space above said horizontal wall constituting a combustion chamber and the space below said horizontal wall constituting a steam chamber, an air heating coil disposed in said pre-heating chamber, means forcing air through said coil, an air nozzle connected to said air heating coil and discharging into the lower portion of said combustion chamber, means discharging powdered fuel into said combustion chamber in a direction intersecting the flow of heated air, a steam generating member in said steam chamber, and means exhausting heated air and products of combustion from said pre-heating and steam chambers.

2. A heater comprising a housing formed of bottom, top, opposite end and side walls, an upright inner wall inwardly from one end wall and spaced at its upper end from said top wall and forming a pre-heating chamber adjacent one end of the housing, a horizontal inner wall fixed to said upright wall and to said side walls, one end of said horizontal wall being spaced from the other end wall, the space above said horizontal wall constituting a combustion chamber and the space below said horizontal wall constituting a steam chamber, an air heating coil disposed in said pre-heating chamber, means forcing air through said coil, an air nozzle connected to said air heating coil and discharging into the lower portion of said combustion chamber, means discharging powdered fuel into said combustion chamber in a direction intersecting the flow of heated air, a steam generating member in said steam chamber, means exhausting heated air and products of combustion from said pre-heating and steam chambers, and means controlling the exhausting of air and products of combustion.

3. A heater comprising a housing including an upper combustion chamber, a steam chamber below and communicating with said combustion chamber, an air pre-heating chamber at one end of said combustion and steam chambers and communicating with said combustion chamber, an air heating and conducting coil in said air heating chamber, an air discharge nozzle extending from said coil and terminating within said combustion chamber, a blower, means connecting said blower with said coil, a steam coil in said steam chamber, an exhaust pipe connected to said air heating chamber, an exhaust pipe connected to said steam chamber, a fuel discharge nozzle communicating with said combustion chamber, a fuel hopper, a conveyor in the lower portion of said hopper, a motor common to said blower and said conveyor, a by-pass pipe connected with said first means and with said conveyor and said fuel nozzle, means regulating the discharge of fuel from said conveyor into said by-pass pipe, and means regulating the exhaust of air and products of combustion from said steam and air heating chambers.

4. A heater comprising a housing including an upper combustion chamber, a steam chamber

below and communicating with said combustion chamber, an air pre-heating chamber at one end of said combustion and steam chambers and communicating with said combustion chamber, an air heating and conducting coil in said air heating chamber, an air discharge nozzle extending from said coil and terminating within said combustion chamber, a blower, means connecting said blower with said coil, a steam coil in said steam chamber, an exhaust pipe connected to said air heating chamber, an exhaust pipe connected to said steam chamber, a fuel discharge nozzle communicating with said combustion chamber, a fuel hopper, a conveyor in the lower portion of said hopper, a motor common to said blower and said conveyor, a by-pass pipe connected with said first means and with said conveyor and said fuel nozzle, means regulating the discharge of fuel from said conveyor into said by-pass pipe, and means regulating the exhaust of air and products of combustion from said steam and air heating chambers.

5. A heater comprising a housing including an upper combustion chamber, a steam chamber below and communicating with said combustion chamber, an air pre-heating chamber at one end of said combustion and steam chambers and communicating with said combustion chamber, an air heating and conducting coil in said air heating chamber, an air discharge nozzle extending from said coil and terminating within said combustion chamber, a blower, means connecting said blower with said coil, a steam coil in said steam chamber, an exhaust pipe connected to said air heating chamber, an exhaust pipe connected to said steam chamber, a fuel discharge nozzle communicating with said combustion chamber, a fuel hopper, a conveyor in the lower portion of said hopper, a motor common to said blower and said conveyor, a by-pass pipe connected with said first means and with said conveyor and said fuel nozzle, a needle valve extending through said by-pass pipe and confronting the discharge end of said conveyor for regulating the quantity of fuel discharged into said by-pass pipe, and means regulating the exhaust of air and products of combustion from said steam and air heating chambers.

6. A heater comprising a housing including an upper combustion chamber, a steam chamber below and communicating with said combustion chamber, an air pre-heating chamber at one end of said combustion and steam chambers and communicating with said combustion chamber, an air heating and conducting coil in said air heating chamber, an air discharge nozzle extending from said coil and terminating within said combustion chamber, a blower, means connecting said blower with said coil, a steam coil in said steam chamber, an exhaust pipe connected to said air heating chamber, an exhaust pipe connected to said steam chamber, a fuel discharge nozzle communicating with said combustion chamber, a fuel hopper, a conveyor in the lower portion of said hopper, a motor common to said blower and said conveyor, a by-pass pipe connected with said first means and with said conveyor and said fuel nozzle, means regulating the discharge of fuel from said conveyor into said by-pass pipe, a regulating damper in each exhaust pipe, means connecting said dampers together for simultaneous operation, said dampers being so arranged that one of said dampers will be disposed in a substan-

tially closed position when the other damper is in an open position.

7. A heater comprising a housing including an upper combustion chamber, a steam chamber below and communicating with said combustion chamber, an air pre-heating chamber at an end of said combustion and steam chambers and communicating with said combustion chamber, an air heating and conducting coil in said air heating chamber, an air discharge nozzle extending from said coil and terminating within said combustion chamber, a blower, means connecting said blower with said coil, a steam coil in said steam chamber, an exhaust pipe connected to said air heating chamber, an exhaust pipe con-

nected to said steam chamber, a fuel discharge nozzle communicating with said combustion chamber, a fuel hopper, a conveyor in the lower portion of said hopper, a motor common to said 5 first means and said conveyor, a by-pass pipe connected with said blower and with said conveyor and said fuel nozzle, a V-shaped coupling connected to said exhaust pipes, a damper in said coupling for regulating the exhaust of air 10 or products of combustion into said coupling, thermostatic means extending into said air heating chamber, and means connecting said thermostatic means with said damper.
